UNITED STATES PATENT OFFICE.

ROSCOE GARDNER PHELPS, OF CLEVELAND, OHIO, ASSIGNOR TO GENERAL ELECTRIC COMPANY, A CORPORATION OF NEW YORK.

SORTING MACHINE.

Application filed August 26, 1920. Serial No. 406,078.

To all whom it may concern:

Be it known that I, ROSCOE GARDNER PHELPS, a citizen of the United States, residing at Cleveland, county of Cuyahoga, State of Ohio, have invented certain new and useful Improvements in Sorting Machines, of which the following is a specification.

My invention relates to measuring or gauging machines and more particularly to 10 automatic machines for gauging glass articles such as rods or tubes although not limited in use thereto.

In lamp making it is preferable that the 15 glass rods and glass tubes be of uniform diameter because of the greater ease of size adjustment. Heretofore, the glass rods, or "cane" glass, and the glass tubing were gauged with the usual type of maximum and minimum limit gauge or with a gauging apparatus such as disclosed in the Gillett application, Serial Number 118,254, filed September 2, 1916. With these gauging means the cane and tubing must be manually handled and usually only in comparatively 25 longer lengths.

My improved gauging means provides for the rapid, automatic handling of short lengths of cane or tubing and the classification of the article gauged into a number of 30 groups of definite dimensional limits. I provide means for feeding the article to the gauging means and means for directing the article after gauging into the proper group determined by the gauging operation. According to my invention it is possible to 35 secure a supply of substantially uniform cane or tubing. Such a supply eliminates size adjustment troubles due to variations in the size of glass used and permits a more satisfactory operation of automatic lamp-making machines in glass working steps. Further advantages of the machine embodying my invention will be apparent from the following specification:

In the accompanying drawing Fig. 1 is a side elevation of a machine embodying my invention and Fig. 2 is a top plan view of the machine of Fig. 1.

Referring to the drawing, the base 10 supports the frame 11 which carries substantially the whole mechanism of the machine. A motor (not shown) through a suitable arrangement such as a belt and pulley drives the shaft 12 which is suitably supported in a

bearing standard 13 on the frame 11. The 55 shaft 12 has attached thereto the arm and disc member 14 of a Geneva motion the Geneva gear 15 being rotatably carried on the shaft 16 and held thereon by a collar 17 the shaft 16 being suitably supported by 60 the bearing standards 18 and 19 on the frame 11. The shaft 16 is given an intermittent reduced speed through the Geneva gear and the following described reducing gears. The Geneva gear 15 through the gear 20 attached 65 thereto drives the idler reducing gear 21 with its smaller gear 22 attached both being supported on a pin in the bearing standard 23 on the frame 11. The gear 22 meshes with and drives the gear 24 fastened to the shaft 70 16. The shaft 16 also has attached the cane glass carrier 25 having oppositely disposed notches 26 for engaging the cane glass 27 as the cane glass is fed from the inclined hopper 28 mounted on the bracket 29 carried 75 by the frame 11.

The gauging mechanism comprises means for actually gauging the cane glass and contacts with means for magnifying the size as gauged and includes a lever 30 pivoted at 31 80 to a bracket 32 on the frame 11 and having a pin 33 with cap 34 adjustably held in the end of the shorter arm of the lever 30 and so placed as to press against a piece of cane glass 27 and gauge it between the drum 35 85 of the carrier 25 and the cap 34 at the proper time. A strong spring 36 attached to the long arm of the lever 30 and the bracket 37 tends to keep the cap 34 against the cane 27. The cap 34 is brought out of engagement 90 with the cane 27 and the drum 35 by means more fully described hereinafter. A series of magnification levers is provided for making more pronounced any variation in size and includes the lever 30. To the long arm 95 of the lever 30 is pivoted a link 38 to the other end of which is pivoted the short arm 39 pinned to a pivot rod 40 rotatably carried in a bearing 41 on the bracket 37. On the other end of the rod 40 is permanently 100 fastened the long arm 42 to the end of which is pivoted the arm 43 which has a slot 44 at the other end for the reception of a pin 45 on one side of the distributing chute 46. A cam 47 fastened to the shaft 48 serves at the 105 proper time to engage the arm 42 to rotate the pivot rod 40 in the bearing 41 and through the link and lever mechanism pre-

viously described force the cap 34 out of engagement with the cane glass 27 and the drum 35 preparatory to the indexing of the carrier. It also allows the cap 34 to gradually engage the cane 27 under the action of the spring 36. The shaft 48 is carried in the standard 49 and in a bearing 50 in the bracket 37 and is driven through the gear 51 attached to the end thereof by the gear 52 fastened to the shaft 12 through the idler gear 53 suitably carried in a standard 54. The distributor 46, which classifies the cane according to size as indicated by the gauging means, is rotatably supported on a rod 55 carried in the frame 11 and working on a threaded portion of the outer end of the rod 55 is nut 56 attached to one end of a helical spring 57 the other end of the spring 57 being fastened to the distributor 46. A lock nut 58 holds the nut 56 so that any desired tension may be given the spring 57 whose normal action is to tend to rotate the distributor 46 to the right as shown in Fig. 1 to ensure engagement with the end of the slot 44 at the proper time. A spring 59 attached to the pin 45 of the distributor 46 and to the pivoted end of the arm 43 also tends to rotate the distributor to the right in the view of Fig. 1. The two fingers 60 on the upper end of the distributor 46 serve to engage either end of the cane 27 to ensure its removal from the carrier 25 to the distributor 46.

In order to lock the distributor 46 into the position given it through the action of the magnification levers, I have provided on the left side of the distributor chute 46 as shown in Fig. 1 a pointer 61 fastened to and projecting beyond the end of the chute 46 and engaging beveled projections 62 equally spaced on an arc shaped portion 63 of the lever 64 pivoted at one end in the bracket 65 carried by the frame 11 and pivoted at the other end to the end of the upright 66. The release of the locking means to allow the distributor to be positioned is accomplished as follows. Near the upper end of the upright 66 is a guide slot 67 for the shaft 48 previously described. Pinned to the upper end of the upright 66 is a roller 68 which rides on a cam 69 fastened to the shaft 48 and having an outline such as to bring the projections 62 on the lever 64 into and out of engagement on the pointer 61 on the chute 46 once during every revolution.

Below the distributor 46, and constructed to correspond to the positions of the distributor 46 as determined by the projections 62 on portion 63 of the lever 64, is a series 60 of delivery chutes 70 which deliver the cane glass received from the distributor 46 to a corresponding series of containers 71 located below the bed 10, half of the containers being back of the containers shown in Fig. 1. The 65 larger sizes of cane fall into containers on

the right side as shown in the view of Fig. 1 and the smaller sizes into the containers on the left side.

In operation the shaft 12 is suitably driven and a supply of cane glass 27 is placed in 70 the hopper 28. The cane 27 is engaged by the notches 26 and taken by the carrier 25 to the gauging position. At this point the cap 34, by the action of the cam 47 and the spring 36, gradually presses the cane against 75 the drum 35 and secures an indication of the size of the cane which is magnified by the lever 30, transmitted by the link 38, again magnified by the combination lever composed of the arm 39, pivot rod 40 and arm 42 80 and transmitted by the arm 43 through the end of the slot 44 to the pin 45 and distributor 46 to position the distributor over the delivery chute 70 corresponding to the size indication gauged, the pointer 61 on the distributor 46 being released from engagement with the projections 62 by the action of the cam 69 as the cap 34 moves forward to gauge the cane and being again brought into engagement with the projections 62 by the 85 action of the cam 69 after an indication of the size is secured and the distributor 46 is positioned over the proper delivery chute 70. The cam 47 now engages the arm 42 to force the cap 34 out of engagement with the cane 27 preparatory to the indexing of the carrier 25. As the carrier 25 moves the cane 27 is engaged by the fingers 60 and falls into the distributor 46 and into the proper delivery chute 70 to be delivered to a container 71 90 corresponding to the indication of size secured by the gauging mechanism. The cycle of operations is then repeated for the next piece of cane.

While I have described a specific embodiment of my invention I do not wish to be limited thereto as various modifications thereof will readily suggest themselves to those skilled in the art.

What I claim as new, and desire to secure 105 by Letters Patent of the United States, is:

1. In a machine for sorting glass articles, a carrier for said glass articles, means for gauging said glass articles and means co-operating with said gauging means for automatically distributing said glass articles after gauging according to size comprising means for removing said glass articles from said carrier, means for receiving said glass articles, a series of magnification levers 110 co-acting with said gauging means and means for causing said magnification levers to position said receiving means comprising a pin mounted on said receiving means, an arm mounted on the end of the series of 115 magnification levers and a slot in said arm for receiving said pin.

2. In a machine for sorting glass articles, a carrier for said glass articles, means for gauging said glass articles and means co-op-

- erating with said gauging means for automatically distributing said glass articles after gauging according to size comprising means for removing said glass articles from 5 said carrier, means for receiving said glass articles, a series of magnification levers co-acting with said gauging means, means for causing said magnification levers to position said receiving means, and means for locking 10 said receiving means in position comprising a pointer mounted on said receiving means, an arm, projections on said arm and means for causing said projections to engage said pointer.
- 15 3. In a machine for sorting articles, a member having its periphery shaped to receive and hold said articles in separate relation to discharge them at a given point and to prevent movement thereof except in the 20 discharge direction, means for rotating said member and means mounted adjacent to the periphery of said member and actuated by engagement with each of said articles for automatically distributing said articles according 25 to the extent of projection of said article in a given direction.
4. In a machine for sorting articles, a member having its periphery shaped to receive and hold said articles in separate relation, to discharge them at a given point and to prevent movement thereof except in the discharge direction, means for rotating said member, a cap, means causing said cap to engage said articles one by one during their 30 travel, a series of distributing chutes and means controlled by the extent of movement of said cap for bringing the proper chute into position to receive the article when discharged.
- 35 5. In a machine for sorting articles, a substantially disc shaped carrying member vertically disposed and having notches at its periphery for receiving and holding said articles in separate relation and for allowing 40 their successive discharge at a given point, means for rotating said member, a cap mov- ably mounted adjacent to said member,
- means for causing said cap to engage said articles in succession as they reach a given point, means for guiding said articles after 50 discharge and means controlled by the extent of movement of said cap for bringing said guiding means into proper position to receive the article engaged by said cap.
6. In a machine for sorting articles, the 55 combination of a hopper having a gravity discharge opening, a vertically disposed rotary disc-shaped member mounted so that a portion of its periphery acts as a closure for the aforesaid opening, and having a series of 60 recesses each shaped to receive and definitely position one of the articles from said hopper, a chute positioned to receive each article as it is discharged from said disc-shaped member, a series of receptacles each for articles of a different size, and gauging means adapted to engage each of said articles when it reaches the discharge position, and comprising means for altering the position of 65 said chute according to the extent of projection of the article to cause said article to be guided to the proper receptacle.
7. In a machine for sorting articles, the combination of a substantially disc-shaped member having a series of substantially 70 horizontally extending recesses at its periphery each adapted to receive and definitely position one of said articles, means for intermittently rotating said disc-shaped member, a chute positioned to receive each article as 75 it is discharged from said disc-shaped member, a series of receptacles each for articles of a different size, and gauging means adapted to engage each of said articles when it reaches the discharge position, 80 and comprising means for altering the position of said chute according to the extent of projection of the article to cause said article to be guided to the proper receptacle.
- In witness whereof, I have hereunto set 90 my hand and seal this 23rd day of August, 1920.

ROSCOE GARDNER PHELPS.
